UNITED STATES PATENT OFFICE.

JOHN F. CLULEY, OF PITTSBURG, PENNSYLVANIA

METHOD OF MAKING DEPRESSED LETTERS OR DESIGNS IN METAL FOR SIGNS.

SPECIFICATION forming part of Letters Patent No. 259,097, dated June 6, 1882.

Application filed January 26, 1882. (No model.)

To all whom it may concern:

Be it known that I, JOHN F. CLULEY, of Pittsburg, county of Allegheny, State of Pennsylvania, have invented or discovered a new and useful Improvement in the Method of Making Depressed Letters or Designs in Metal for Signs; and I do hereby declare the following to be a full, clear, concise, and exact description thereof.

My present invention relates to the manufacture of metal signs of that class in which a seat for the letter, or of the shape of the letter or other character, as a monogram or design of any desired kind, is made by the use of acids. Such signs are usually made on a plate or sheet of zinc or brass or other metal or metallic alloy. Heretofore the most common practice has been to apply varnish to the plate or sheet immediately along the edge of and around the letter, design, or other character to be made, and then apply a suitable acid, such as will eat away the metal thus left uncovered, the coating of varnish being intended to protect the metal outside the edge. In this operation it has been found that the acid sometimes eats under the varnish along the edge of the letter or other space so uncovered, so as to give a slightly-ragged edge, which has to be trimmed down in order to get good work. In the seat thus made the lettering or ornamentation is done.

I have found that a layer of tin-foil or other soft metal not affected by acids as used in such work entirely prevents or guards against the liability of the acid to eat into the metal around the surface edge of the letter or other design, and thereby form or produce a ragged edge. In using it I prepare the sign, sheet, or plate in the usual way, and apply a coating of varnish most conveniently over the part on which the letter or other seat is to be made, and for a short distance outside the edge of such seat or over the whole plate. On this I lay a sheet or coating of tin or lead foil or other suitable soft metal, in a thin sheet, such as is not liable to be attacked to any injurious extent by the acids commonly employed in such work. The form or outline of the lettering, design, monogram, character, or ornamentation is then cut in or out of the tin-foil

or other metallic coating and out of the varnish by the use of suitable tools, whereby the face of the metal where a letter or other character or design is required is laid bare. The varnish, however, will not, if the work is done with proper speed, become fully solidified. As a result of such fact, so much of the tin-foil and varnish as are included within the lines of cut will readily strip off and leave a border of tin-foil, or its described equivalent, along outside of each border-line of the letter or other character. The acid is then applied in the ordinary way, and left on for the usual length of time, or longer, if necessary or desired. The subsequent part of the work of making the sign need not be described, as it forms no part of the present invention.

The method of operation thus described is illustrated in the accompanying drawings, wherein—

Figure 1 shows a sheet of metal with the coatings thereon, and a seat for the letter A uncovered therein. Fig. 2 is a cross-section through Fig. 1 in the plane of the line *xx*, but with the letter-seat simply uncovered; and Fig. 3 shows the same sectional view to an enlarged scale, but with the seat eaten out.

The sheet-metal plate on which the sign is made is represented at B. *a* represents the coating of varnish, and *b* the soft-metal foil. In cutting out the foil and varnish, in order to uncover the seat, these materials will ordinarily be pressed down, as illustrated at *c*. The surface edges of the seat to be eaten out by acids will thus be protected, and the seats for the letter or other character or design will be eaten out, as at *e*, to any desired depth. Beneath the surface the acids may eat out laterally to a slight extent; but this will work no injury, as the main point is to protect the surface. In fact, the widening of the bottom of the seat, as at *a*, will be an advantage, as the material placed in the seat will thereby be held more securely in place.

I have had this invention in use for some time, (but for less than two years in public,) and have found that, for some reason which I cannot explain, the tendency of the acid to eat into the metal edgewise along the border-line of the letter or other character or designation

is effectually guarded against or prevented, so that after the acid has done its work a clean-cut seat with regular edges, as desired, is made for the lettering or other marking or ornamentation, as called for; also, the acid need not be removed so promptly as heretofore, but may be left on longer, so as to eat out a deeper seat, and no injury will result therefrom.

I claim herein as my invention—

- The method of making depressed letters, characters, or designs for a sign in a metal plate, consisting in applying a varnished coating to the plate and applying a metallic foil

over the varnished coating, and then cutting the design, characters, or letters through the metal foil and varnish to the plate, and then applying acid on the plate through the design, substantially as described, and for the purpose set forth.

In testimony whereof I have hereunto set my hand.

JOHN F. CLULEY.
